Yang et al., "Communications Headset," Design U.S. Appl. No. 29/523,218, filed Apr. 7, 2015.

(Continued)

Primary Examiner — Paula Greene

CLAIM

The ornamental design for a communications headset, as shown and described.

DESCRIPTION

FIG. 1 is a front-right-perspective view of a communications headset showing my new design;

FIG. 2 is a back-left-perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The broken lines showing the unclaimed features form no part of the claimed design.

1 Claim, 7 Drawing Sheets(56)
